UNITED STATES PATENT OFFICE.

FRANK W. HARRINGTON, OF SEBASTOPOL, CALIFORNIA.

SIGNAL.

1,115,668.

Specification of Letters Patent.

Patented Nov. 3, 1914.

Application filed June 11, 1913. Serial No. 773,102.

To all whom it may concern:

Be it known that I, FRANK W. HARRINGTON, a citizen of the United States, residing at Sebastopol, in the county of Sonoma, 5 State of California, have invented certain new and useful Improvements in Signals; and I do hereby declare the following to be a full, clear, and exact description of the invention, such as will enable others skilled in 10 the art to which it appertains to make and use the same.

This invention relates to signals and particularly to a type adapted for signaling in a fog from vessels on the high seas. 15 The object of the invention resides in the provision of a signal of the type named which can be made to intermittently emit flashes of great intensity.

With the above and other objects in view 20 the invention consists in the detail of construction and in the arrangement and combination of parts to be hereinafter more fully described and particularly pointed out in the appended claims.

25 In describing the invention in detail reference will be had to the accompanying drawings wherein like characters of reference denote corresponding parts in the several views, and in which—

30 Figure 1 is a view in elevation of the mast of a vessel showing the improved signal applied; Fig. 2, a vertical section of what is shown in Fig. 1; Fig. 3, a section on the line 3—3 of Fig. 1, and Fig. 4, a plan view 35 of what is shown in Fig. 1.

Referring to the drawings 10 indicates the mast or any other suitable pole mounted aboard a vessel. Secured to this mast or pole 10 longitudinally of the latter is a casing 11 the lower end of which communicates with a hopper 12 suitably mounted on the casing. The upper end of the casing 11 is provided with an opening 13 which communicates with an inclined passage 14 40 formed in the mast or pole 10. Mounted within the casing 11 is an endless conveyer 15 provided with a plurality of cups 16 and operated through the medium of a crank handle 17. Mounted upon the mast or pole 45 10 are spaced metallic contact members 18 and 19 the upper ends of which are positioned to receive material delivered through the passage 14 therebetween. These contact

members 18 and 19 are connected by wires 20 and 21 with a suitable electric source E. 55

In the operation of the signal a supply of fusible balls 22 are deposited in the hopper 12 and the conveyer 15 operated. During this operation of the conveyer 15 the ball 22 will be deposited in the cups 16 and elevated. As the cups pass the opening 13 the balls carried thereby will be successively discharged into the passage 14. From this passage 14 the balls 22 will pass between the contact members 18 and 19 and close the 60 electric circuit generated by the source E. As soon as this circuit is closed the ball between the contact members 18 and 19 will be fused and a flash of great intensity will result which can be seen for a considerable 65 distance in a fog. The rapidity of these flashes can of course be regulated by the rapidity by which the conveyer 15 is operated and signaling may be continued as long as a supply of fusible balls is maintained in 70 the hopper 22.

What I claim is:—

1. In a signaling device, the combination of a support, an electric circuit, spaced terminal contacts included in said circuit and 80 mounted on said support, the free ends of said terminal contacts being flared, and means for intermittently delivering loose fusible elements between the free ends of said contacts whereby the circuit is intermittently closed and the fusible elements 85 successively consumed.

2. In a signaling device, the combination of an upright having an inclined passage in its upper end, a supply of loose fusible elements, means for transferring the elements singly from the supply and delivering same into said passage, an electric circuit, spaced terminal contacts included in said circuit and mounted on said uprights in position to 90 receive the fusible elements successively therebetween from said passage whereby the circuit is intermittently closed and the fusible element successively consumed.

In testimony whereof, I affix my signature, in the presence of two witnesses.

FRANK W. HARRINGTON.

Witnesses:

WILLIAM S. BORBA,
CHARLES F. CHASE.
